FURNACE FIRE BOX AND ARCH STRUCTURE

John C. Chapple, St. Louis, Mo.

Application May 29, 1931, Serial No. 540,948

5 Claims. (Cl. 122—68)

This invention relates to furnace fire box and arch structures, and has for its primary object and purpose to provide the fire box with water circulating elements extending therethrough having means for supporting an arch wall composed of refractory bricks or units of standard form and with the rear upper end of the wall downwardly curved or inclined to deflect the course of flow of the products of combustion into contact with the fire door, side and crown sheets of the fire box.

The novel feature of my invention in this respect is more particularly characterized by an improved type of water circulating element extending through the fire box upon which the arch is supported so constructed as to obviate the formation of steam holding or retaining pockets.

It is also another object of the invention to provide the fire box with one or more siphons extending between the throat sheet and crown sheet thereof and water circulating means connecting the rear ends of the siphons with the fire door sheet.

A further object of the invention in one form thereof resides in the provision of an auxiliary arch supported upon the water circulating tubes in rearwardly spaced relation to the main arch for the purpose of retarding the flow of the products of combustion rearwardly above said main arch thereby obtaining a comparatively prolonged heating effect upon the fire door sheet and crown sheet of the fire box.

With the above and other objects in view, the invention consists in the improved furnace fire box and arch structure as will be hereinafter more fully described, illustrated in the accompanying drawings, and subsequently incorporated in the subjoined claims.

In the drawings, wherein I have disclosed two simple and practical embodiments of the essential features of my improvements, in which similar reference characters designate corresponding parts throughout the several views,—

Fig. 1 is a vertical section through a locomotive fire box, this view being taken on the line 1—1 of Fig. 2, and illustrating the application of the arch structure to an alternating arrangement of water circulating tubes and siphons;

Fig. 2 is a sectional view taken substantially on the line 2—2 of Fig. 1, the ends of the arch tubes and the fire box wall being shown in elevation;

Fig. 3 is a vertical section taken substantially on the line 3—3 of Fig. 4, showing another embodiment of the invention;

Fig. 4 is a vertical sectional view taken on the line 4—4 of Fig. 3, the ends of the arch tubes and the fire box wall being shown in elevation, and

Fig. 5 is a detail perspective view of one of the spacer brick used in the auxiliary arch shown in Fig. 3.

Modern high powered locomotives are provided with boiler fire boxes of appreciably greater length than those heretofore used in standard locomotive boiler construction, and if the conventional type of arch is proportionately extended rearwardly towards the fire box door sheet, the space between the top of the arch and the crown sheet is too greatly restricted. If the comparatively short arch is used, the products of combustion pass over the rear end of the arch forwardly to the boiler flues together with considerable fine coal unignited or only partially consumed and are not brought into contact with the fire door sheet and rear portions of the side sheets and crown sheet of the fire box. This results in inadequate steam production and uneconomical consumption of fuel. In a co-pending application for patent filed of even date herewith, I have disclosed an improved arch structure for use in connection with relatively long fire boxes having its upper rear end embodying means for deflecting the products of combustion downwardly towards the fuel bed and in contact with the rear side sheets, fire door sheet and crown sheet of the fire box and which obviates undue restriction of the space between the top of the arch and the crown sheet. In order to enable this arch to be used in conjunction with water circulating tubes and siphons of conventional form, I have disclosed in said application, refractory tile or brick constituting the upper end of the arch of a certain novel form and construction.

I propose, by means of my present invention to accomplish this same general result with the use of an arch composed wholly of refractory bricks or units of standard form.

In the drawings wherein I have illustrated the essential feature of my invention as applied to a locomotive fire box, 5 designates the fire door sheet at the rear end of the fire box, 6 the flue sheet at the forward end thereof, 8 the crown sheet, and 9 the throat sheet extending downwardly from the flue sheet in rearwardly offset relation thereto. In these respects, the boiler fire box is of conventional form, and it will therefore, be understood that the boiler water surrounds and is in direct contact with the outer surfaces of these metal walls or sheets of the fire box.

Obliquely inclined water circulating tubes extend longitudinally through the fire box from the throat sheet 9 to the fire door sheet 5. As herein shown, each of these tubes includes a rear section 10 opening at its lower end through the throat sheet 9, said tube section having a lower portion of somewhat greater radius than the upper portion thereof to provide longitudinally extending shoulders 11 on each side of said tube section. The upper end of the tube section 10 on its lower side, is longitudinally curved as indicated at 12, the shoulders 11 extending throughout this curved part of the tube in concentric relation thereto. The upper portion of the tube at this curved section 12 gradually merges into the vertically elongated or flattened upper section 13 of the tube which opens at its upper end through the fire door sheet 5 adjacent to the crown sheet 8. The walls of the lower curved portion 12 of the tube and the shoulders 11 are gradually merged into the opposite side walls of the flattened tube sections 13 so as to avoid the formation of internal steam holding or retaining pockets in the tube walls.

In Figs. 1 and 2 of the drawings, I have shown vertically disposed siphons 16 within the fire box alternately arranged with respect to the water-circulating tubes of the form above described. These siphons have upper longitudinally elongated portions which open through the crown sheet 8, and at their lower ends are provided with forwardly and downwardly extending tubular portions opening through the throat sheet 9. These tubular portions are of the same cross sectional form as the portions 10 of the water-circulating tubes and disposed in the same plane therewith. Also above these tubular extensions of the siphons, the lower ends thereof are of the same cross sectional form and are longitudinally curved in the same manner as the parts 12 of the tubes, as will be evident from reference to the drawings. The lower portion of the siphon and its forward tubular extension are provided with shoulders 11' on opposite sides thereof to receive and support one end of the arch bricks 14 which extend between the siphon and the adjacent water-circulating tubes.

Thus it will be seen that a series of alternating water circulating tubes and siphons in any desired number may be arranged in transversely spaced relation through the fire box and upon the shoulders 11 and 11' of these spaced tubes and siphons, respectively, the arch forming brick or tile of refractory material indicated at 14 being supported at their opposite ends, thus preventing the direct passage of the products of combustion upwardly between the tubes and siphons in this portion of the fire box and causing the same to flow longitudinally along and in contact with said tubes and siphons in the rear ends of the arch wall. The brick 14 are of a standard form widely used in such locomotive arches, having upper and lower curved surfaces with the lower concave surfaces thereof opposed to the fuel bed. As seen in Figs. 1 and 2 of the drawings, by reason of the curved rear end portions of the shoulders 11 and 11' of the supporting tubes and siphons, the brick forming the rear end of the arch wall will be successively supported at different angles and together, form a rearwardly extending downwardly curved or inclined deflecting section so that the gases and products of combustion will be directed by said upper rear end of the arch wall, rearwardly and downwardly towards the fuel bed and into contact with the fire door sheet 5. Any solid fine particles of fuel carried in suspension by the gases are thus returned to the zone of intense heat where they will be ignited. Thus, by causing the products of combustion to directly contact with and flow upwardly along the fire door sheet 5, a maximum percentage of the heat units will be utilized in the conversion of the water into steam. Also, the products of combustion are thereby caused to come into direct contact with the rear end portion of the crown sheet 8, with the elongated portions of the siphons, and as well with the portions 13 of the water circulating tubes having a relatively extensive wall area. This further increases the maximum extraction of heat from the burning gases and the generation of steam in the boiler.

While any preferred means may be provided for the purpose of retaining the rear downwardly inclined brick 14 of the arch upon the supporting shoulders 11 and 11', for this purpose, I prefer to weld or otherwise permanently secure to the opposite sides of the water circulating tubes and siphons the short lugs or trunnions indicated at 15 which effectively prevent the rearward sliding movement of the fire brick.

In Figs. 3 and 4 of the drawings, I have shown an auxiliary rear arch spaced from the main arch wall. For the purpose of supporting this auxiliary arch in position, the side walls of the flattened sections 13 of the water circulating tubes are formed with outwardly struck ribs indicated at 17 which are inclined downwardly and rearwardly across said tubes towards the fire door sheet 5. The rear ends of the siphons 16 are connected by water circulating means with the fire door sheet 5, and in this instance, this water circulating means is in the form of the tubes 18 which extend substantially in parallel relation to the ribs 17 and are suitably connected with the rear end walls of the siphons and the fire door sheet 5. Upon these tubes 18 and the ribs 17 of the adjacent main arch supporting tubes the opposite ends of the refractory brick or tile 19 are supported. These brick may be of the same standard form as the brick 14 constituting the main arch. The rear brick 19 are spaced from the fire door sheet 5 by means of suitable spacer brick indicated at 20 which are arranged on the tubes 18, thus providing openings between the rear end of the arch formed by the brick 19 and the fire door sheet. These spacer brick may be of any suitable length as circumstances or conditions may require.

In this last described form of the invention, it will be understood that after the products of combustion are directed rearwardly and downwardly by the upper end of the main arch wall against the fire door sheet, their upward course of flow along the fire door sheet will be retarded by the auxiliary arch wall composed of the bricks 19, thus securing a very intensive concentrated heating effect upon the fire door sheet 5. The products of combustion pass at relatively low velocity upwardly through the spaces in the auxiliary arch formed by the spacer brick 20 and into contact with the rear end of the crown sheet where further heat is extracted therefrom before the evaporation of the boiler water. Also by the provision of the tubular water circulating connections between the fire door sheet and the rear ends of the siphons 16, better and freer circulation of the water through the siphons is obtained.

which likewise increases the rapidity of steam generation to the maximum boiler capacity.

From the foregoing description considered in connection with the accompanying drawings, the 5 construction, manner of operation and several advantages of my present invention will be clearly and fully understood. As my copending application for patent above referred to discloses the novel mounting and arrangement of the 10 main arch whereby the flow of the products of combustion is deflected into contact with the rear fire door sheet, it will be understood that this feature is not herein broadly claimed, the principal feature of novelty in my present invention, 15 residing in the novel construction of the water circulating tubes and siphons, whereby the advantages of the invention disclosed in my copending application may be obtained with the use of arch wall brick of ordinary standard form 20 throughout the structure of the arch.

I have herein shown several embodiments of the essential features of my invention, but it is to be understood that the same might also be incorporated in various other alternative structural forms, and I accordingly reserve the privilege of adopting all such legitimate changes therein as may be fairly incorporated within the spirit and scope of the invention as claimed.

I claim:

30 1. In a locomotive boiler furnace, transversely spaced water circulating elements having parts longitudinally inclined upwardly from the fire box throat sheet, an arch wall composed of refractory brick, and said parts of the water circulating elements at each side thereof being formed with longitudinally extending supporting shoulders for the arch brick having their upper end portions downwardly curved towards the fuel bed, an auxiliary arch wall above and 40 in rearwardly spaced relation from said first named arch wall, and means associated with said water circulating elements supporting said auxiliary arch wall in a longitudinally inclined position extending rearwardly and downwardly towards the door sheet of the fire box.

2. In a locomotive boiler furnace, transversely spaced water circulating elements having parts longitudinally inclined upwardly from the fire box throat sheet, an arch wall composed of refractory brick, and said parts of the water circulating elements at each side thereof being formed with longitudinally extending supporting shoulders for the arch brick having their upper end portions downwardly curved towards the fuel bed, an auxiliary arch wall above and in rearwardly spaced relation from said first named arch wall, means associated with said water circulating elements supporting said auxiliary arch wall in a longitudinally inclined position extending rearwardly and downwardly towards the door sheet of the fire box, and spacer brick interposed between

the auxiliary arch and the fire door sheet providing passages for the upward flow of the products of combustion in contact with the upper end of said door sheet and the rear end of the crown sheet of the firebox.

3. In combination with a locomotive boiler fire box and transversely spaced water circulating elements extending through said fire box, said elements including siphons connected with the fire box throat sheet and the crown sheet and 10 terminating at their rear ends in spaced relation from the door sheet of the fire box, a main arch wall supported by said elements extending upwardly from the throat sheet and terminating in 15 spaced relation from the rear ends of the siphons, and an auxiliary arch wall and supporting means therefor connecting the rear ends of the siphons with the fire box door sheet, said latter arch wall being disposed above and in rearwardly spaced 20 relation from said main arch wall.

4. In combination with a locomotive boiler fire box and transversely spaced water circulating elements extending through said fire box, said elements including siphons connected with the fire box throat sheet and the crown sheet and 25 terminating at their rear ends in spaced relation from the door sheet of the fire box, a main arch wall supported by said elements extending upwardly from the throat sheet and terminating in 30 spaced relation from the rear ends of the siphons, water circulating tubular connections between the rear ends of the siphons and the door sheet of the fire box, other water circulating elements extending rearwardly of the siphons and connected with 35 said door sheet, and an auxiliary arch wall supported by the latter elements and said tubular connections above and in rearwardly spaced relation from the main arch wall.

5. In a locomotive boiler furnace which includes transversely spaced water circulating elements inclined in the direction of their length upwardly and forwardly toward the fire box door sheet from the fire box throat sheet, shoulders formed on said elements in the direction of the length thereof from said throat sheet and having 40 their upper front end portions curved downwardly toward the fire box fuel bed, an arch wall composed of refractory brick supported on said shoulders including the downwardly curved end portions thereof, extensions on certain of said 45 elements extending upwardly to the fire box crown sheet, their rear ends spaced a distance from the fire box flue sheet and their front ends extending well beyond the downwardly curved end of the arch wall but spaced from the fire box door sheet, 50 and extensions on certain other of said elements lying between the projected outlines of the first named extensions and extending rearwardly to 55 the fire box door sheet.

JOHN C. CHAPPLE. 60
